US00D973314S

(12) United States Design Patent (10) Patent No.: US D973,314 S
(45) Date of Patent: * Dec. 27, 2022

(54) ATHLETIC SANDAL

(71) Applicant: Anatomic Research, Inc., Jasper, FL (US)

(72) Inventor: Frampton E. Ellis, Jasper, FL (US)

(73) Assignee: Anatomic Research, Inc., Jasper, FL (US)

() Term: 15 Years

(21) Appl. No.: 29/802,394

(22) Filed: Aug. 4, 2021

(51) LOC (13) Cl. 02-04

(52) U.S. Cl.

USPC D2/916; D2/902

(58) Field of Classification Search

USPC D2/896-900, 914-917, 909, 930, 943,
D2/946, 969-972
CPC .. A43B 3/10; A43B 3/12; A43B 3/12; A43B
3/126-128
